UNITED STATES PATENT OFFICE.

CHARLES E. WHITE, OF PHILADELPHIA, PENNSYLVANIA, ASSIGNOR TO THE UNITED GAS IMPROVEMENT COMPANY, OF SAME PLACE.

HYDROCARBON-LAMP.

SPECIFICATION forming part of Letters Patent No. 586,299, dated July 13, 1897.

Application filed October 15, 1896. Serial No. 608,977. (No model.)

To all whom it may concern:

Be it known that I, CHARLES E. WHITE, a citizen of the United States, residing at the city of Philadelphia, in the county of Philadelphia and State of Pennsylvania, have invented certain new and useful Improvements in Hydrocarbon-Lamps, of which the following is a specification.

The object of my invention is to provide means for automatically forcing a proper supply of liquid or fluid fuel to a hydrocarbon-burner.

To this end use is made in my invention of the capillary or similar action of a wick for automatically feeding proper quantities of fluid from a reservoir or fount to a vaporizer exposed to the heat of a hydrocarbon-burner and adapted to vaporize and return all of it to the fount or reservoir, where it creates a pressure which forces liquid fuel from the fount or reservoir to the hydrocarbon-burner.

The nature, characteristic features, and scope of my invention will be more fully understood from the following description, taken in connection with the accompanying drawings, forming part hereof, in which—

Figure 1 is a side view, partly in section and partly in elevation, of a lamp embodying features of my invention and adapted for use in connection with a Welsbach or other incandescent mantle. Fig. 2 is a similar view illustrating a modification of a lamp embodying features of my invention, and Figs. 3 and 4 are detached views illustrating parts shown in Fig. 2.

In the drawings, *a* is a fount or reservoir provided with a valved inlet for filling it and adapted to contain a supply of fluid or liquid hydrocarbon fuel.

b is a hydrocarbon-burner provided with regulating-cocks, as *c* and *c'*, and adapted to receive a supply of liquid fuel by way of a pipe *d*, that communicates with the fount or reservoir *a*. This burner *b* is constructed to volatilize liquid hydrocarbon fuel and cause it to be mixed with air and then burned.

e is a Welsbach or other type of mantle or incandescent. These parts are well known, and in order to produce from them the most satisfactory illuminating effect liquid hydrocarbon fuel should be fed under pressure or

forced from the reservoir or fount *a* by way of the pipe *d* to the hydrocarbon-burner. I accomplish this result by causing waste heat from the burner to volatilize portions of the liquid fuel and by then returning the resulting vapor to the fount or reservoir, where it affords the necessary pressure for effecting the required forced feed. Obviously this may be done by a variety of arrangements and of dispositions of parts, but I will proceed to describe the best means known to me for carrying my invention into effect.

f is a vaporizer exposed to the heat of the burner. As shown in the drawings, it is located centrally above it, but the location is not important so long as it is heated sufficiently to vaporize the fluid fuel.

A pipe, passage, or conduit *g* affords means for conveying liquid fuel from the fount or reservoir to the vaporizer, and a pipe, passage, or conduit *h* affords means for conveying vapor from the vaporizer to the interior of the fount or reservoir. A wick *g'* by its capillary action is well adapted to insure a constant and regulated supply of fluid fuel or hydrocarbon to the vaporizer. The pipe, passage, or conduit *h* discharges vapor above the supply of fluid in the reservoir or fount and preferably near the top thereof.

As shown in Fig. 1, the pipes *g* and *h* are nested or arranged concentrically one within the other. The vaporizing-chamber is formed by a cap at their lower ends, and communication between them is provided, for example, by means of openings, as *i*. At its upper end the pipe *g* is fitted to a socket or plug carried at the upper end of a tube *j*, formed in the bottom of the tank or reservoir. At its upper end the pipe *h* may extend slightly above the upper end of the pipe *g*, as shown, in order to prevent ingress of oil.

As shown in Figs. 2, 3, and 4, the pipes *g* and *h* are not nested, but they and the vaporizer *f* are arranged as shown.

In Fig. 1 the fount or reservoir may be enveloped by asbestos *k* or by an air-space *l*, or both, which constitute a covering for excluding heat. The heat-excluding covering, which lies between the pipe *g* and the walls of the tube *j*, prevents undue heating of the contents of the reservoir or fount. A collar

m and deflector *m'* are connected with sleeves *m²*, adapted to slide on the supply-pipe *d* and on a rod or pipe *m³* and to be clamped to place by means of set-screws *m⁴*. The collar 5 *m* carries the globe *n* and a hinged cap *o*, which normally serve to cover the burner. When the cap *o* is opened, the collar, globe, and deflector may be pushed up in order to permit of the lighting or adjustment of the 10 burner. The deflector *m'* is provided with the usual vent and wind-cap and with an opening for the accommodation of the lower ends of the pipes *g* and *h* and serves to concentrate heat upon the vaporizer *f*.

15 The mode of operation of apparatus embodying features of my invention may be described in connection with the accompanying drawings as follows: The wick *g'* by its capillary action supplies liquid hydrocarbon by 20 way of the pipe, passage, or conduit *g* to the vaporizer in proper limited quantities. The vaporizer, by reason of heat imparted to it from the burner, vaporizes or volatilizes the liquid hydrocarbon so supplied to it, and this 25 vapor passes by way of the pipe, passage, or conduit *h* into the interior of the fount or reservoir and above the contents thereof, and thus serves to force the liquid contents to the burner *a* by way of the pipe *d* under that 30 pressure or forced feed which is best adapted for causing the burner to volatilize fluid fuel and burn it in combination with air in such manner that the best illuminating effect is produced from the mantle or incandescent *e*.

35 It will be obvious to those skilled in the art to which my invention appertains that modifications may be made in details without departing from the spirit thereof. Hence I do not limit myself to the precise construction 40 and arrangement of parts hereinabove set forth and illustrated in the accompanying drawings; but,

Having thus described the nature and objects of my invention, what I claim as new, 45 and desire to secure by Letters Patent, is—

1. The combination with a pressure apparatus comprising a closed vaporizer having inlet and outlet pipes communicating with a

reservoir or fount, of a wick interposed in said inlet-pipe for supplying fluid to the vaporizer 50 in limited quantity, and a separate pipe leading from the reservoir or fount and provided with a hydrocarbon-burner, substantially as described.

2. The combination with a pressure apparatus comprising a closed vaporizer having inlet and outlet pipes communicating with a fount or reservoir, of a separate pipe leading from the fount or reservoir and provided with a hydrocarbon-burner, substantially as de- 60 scribed.

3. In combination, a reservoir having a tube, a burner and burner-supply pipe communicating with said reservoir, nested pipes 65 accommodated by said tube and communicat- ing at their upper ends with the interior of the reservoir and closed at their lower ends to form a closed vaporizer exposed to the heat of the burner, and a wick in one of said pipes, substantially as described.

4. In combination a reservoir and its burner- 70 pipe and hydrocarbon-burner, nested pipes whereof one contains a wick and whereof both communicate with the interior of the reservoir, a cap closing the lower ends of said pipes 75 to form a vaporizer in communication with both of them, and a deflector surrounding the vaporizer and burner, substantially as described.

5. In combination a reservoir, a rod and a 80 burner-supply pipe suspending a hydrocarbon-burner from the reservoir, nested pipes whereof one contains a wick and whereof both communicate with the interior of the reservoir and with each other at their lower 85 ends which are closed in proximity with the burner to form a vaporizer, and devices mounted so as to slide on said rod and pipe and adapted to cover and uncover the burner, substantially as described.

In testimony whereof I have hereunto signed my name.

CHARLES E. WHITE.

In presence of—

THOS. A. JAMES,
F. H. MACMORRIS.
